UNITED STATES PATENT OFFICE

2,418,150

THERMAL RESPONSIVE ELEMENT

John R. Adriansen, Cincinnati, Ohio, and Robert N. Eck, Whitefish Bay, Wis., assignors to Cutler-Hammer, Inc., Milwaukee, Wis., a corporation of Delaware

Application September 20, 1943, Serial No. 503,026

1 Claim. (Cl. 297—3)

1

This invention relates to thermal responsive elements of the expandable fluid type having a closed capillary tube extension for mounting within a well.

Thermal elements of the aforesaid type are commonly used in switches for effecting temperature control of refrigerating apparatus such as electric water coolers. In such installations the water to be cooled is contained in a tank under considerable pressure and cooling coils are mounted either within the tank or upon the exterior thereof. Also the tank is commonly provided with a deep well for receiving the capillary tube extension of a temperature control switch to enable mounting of the switch in an accessible location outside the tank and to also facilitate rapid heat transfer between the water and the capillary tube as is required for close temperature regulation. However, it has heretofore been difficult to obtain good thermal contact between the capillary tube and the inner surface of the well, and the general object of the present invention is to provide an improved capillary tube construction which overcomes this difficulty.

Another object is to provide an improved capillary tube construction having a resilient portion which is flexed upon insertion into the well to insure proper positioning and good thermal contact of the tube within the well.

Various other objects and advantages of the invention will hereinafter appear.

The accompanying drawing illustrates an embodiment of the invention which will now be described, it being understood that various modifications may be made in the embodiment illustrated without departing from the spirit and scope of the appended claim.

In the drawing,

Figure 1 is a side elevational view of a thermal responsive element embodying the invention;

Fig. 2 is a side elevational view of the capillary tube shown in Fig. 1 with the tube turned 90 deg. from the position shown in Fig. 1;

Fig. 3 is a sectional view illustrating the capillary tube within a well, and

Fig. 4 is an enlarged sectional view on line 4—4 of Fig. 3.

Referring to Fig. 1, the same illustrates a thermal responsive element of the expandable fluid type comprising a capillary tube 1 having one end connected to an expandable diaphragm device 2 and having its other end sealed. The tube 1 is preferably formed of copper and said tube and the diaphragm device 2 are filled with a suitable expandable fluid which causes the pressure within the diaphragm device 2 to increase and decrease upon an increase and decrease in temperature in the coolest part of said tube.

As shown in Figs. 1 and 2, tube 1 is provided with a long stem portion 3 and a short resilient

2

end portion which is formed by two oppositely disposed spaced hairpin bends 4 and 5. The bends 4 and 5 are disposed at an angle to each other and provide legs 6 and 7 which are disposed in triangular relation with respect to the stem portion 3. As shown in Fig. 1, leg 6 diverges slightly with respect to the stem portion 3 and leg 7 diverges slightly with respect to leg 6.

As hereinbefore set forth, electric water coolers are commonly provided with a tank which contains the water and is provided with a deep well for receiving the capillary tube extension of a temperature control switch to enable mounting of the switch outside the tank and to also facilitate rapid heat transfer between the water and the capillary tube, as is required for close temperature regulation.

Fig. 3 illustrates the well member 8 of a water cooler and also illustrates the above described capillary tube in assembled position within said well. The diameter of well 8 is such that upon insertion of tube 1 therein the legs 6 and 7 on the end of said tube are flexed with respect to each other and with respect to the stem portion 3. Thus when the tube is inserted into the open end of well 8 and slid into the position shown in Fig. 3 the legs 6 and 7 and stem 3 yieldingly engage the inner surface of the well, as shown in Fig. 4, to insure good thermal contact of the tube within the closed end of the well, as is required for proper temperature regulation of refrigerating apparatus such as water coolers.

What we claim as new and desire to secure by Letters Patent is:

35 A thermal responsive element having a closed fluid containing capillary tube extension for insertion within an associated cylindrical well, said tube extension having spaced oppositely disposed hairpin bends forming an end portion consisting of a short end leg and a short intermediate connecting leg between said end leg and the body of said tube, said legs being spaced with respect to each other and with respect to the body of said tube to provide for torsional stressing of said tube 40 in the intermediate leg portion thereof and transverse stressing of said tube at said bends upon insertion of the end portion thereof within said well to thereby insure good thermal contact of said tube with the interior surface of said well.

50 JOHN R. ADRIANSEN.
